TOY MONORAIL TRAIN AND HANDCAR

Constantin Paul Lent, Forest Hills, N. Y.

Application June 5, 1939, Serial No. 277,388

6 Claims. (Cl. 105—141)

This invention relates to monorail toy trains, monorail toy hand cars and to such toys by which a set of figures are given a realistic animated movement. These figures may represent newspaper strip comics, "Mickey Mouse," animal cartoons and such like.

An object of this invention is a monorail toy train or monorail toy hand car which will operate upon one rail and that is comparatively inexpensive to manufacture and safe to operate.

Another object of this invention is to provide a monorail train or hand car and means thereon for retaining such a train or hand car in straight and upright position on a single rail when such car is not in motion, stands still, and when it is in operation.

A further object of this invention is to provide a practical monorail gage of such construction as to be used with spring driven monorail trains or hand cars or with such electrically driven cars.

Another object of this invention is to provide a practical and efficient interconnecting means for connecting one rail link to another link.

Other objects and features will appear from the following detailed specification and the accompanying drawings. Referring to the drawings:

Fig. 1 is a side-view elevation of a monorail hand car.

Fig. 2 is a plan-view elevation of the monorail hand car shown in Fig. 1.

Fig. 3 is a section on the line 3—3 of Fig. 1.

Fig. 4 is a detailed view of the connection between sections of a monorail.

Fig. 5 is a section on the line 5—5 of Fig. 1.

Fig. 6 is a view of the hand car from the side opposite to that shown in Fig. 1. This view corresponds with the view taken on the line 6—6 of Fig. 5.

Fig. 6a shows a modification of a spring support for a monorail train.

Fig. 7 shows a monorail hand car operated through a spring wound motor. It also shows a hingeably mounted handle for winding the motor.

Fig. 8 is a section through a modified connection for a monorail joint.

Fig. 9 is a side-view of the monorail connection shown in Fig. 8.

Fig. 10 shows a front-view of a monorail car.

Fig. 11 is a side-view of the monorail hand car shown in Fig. 10.

Fig. 12 is a modified arrangement for supporting a monorail hand car or train on a monorail.

Referring to Fig. 1, numeral 20 represents a toy hand car which consists of a left side frame 21 and a right side frame 21x. The side frames 21 and 21x have base extensions 22 and 23. At the hinging point 24 there is mounted a hinging arm 25. At both ends 26 of the hinging arm 25 a pair of articulated animated figures 27 are hingeably held. The figures 27 can represent animals, news-

paper strip comics and such like. In Fig. 1, both of the figures 27 are animated. Although more than two figures can be used some may stand still and others may be animated. The hinging arm 25 is rocked by the rocking arm 28. The lower end of the rocking arm 28 is held by an eccentric crank member 29 which is fastened on the operating or driving shaft 31. A pair of single driving wheels 32 are also fastened to the shafts 30 and 31. The wheels 32 consist of a double flanged roller. When they are placed over the monorail the flanges of the wheels grip the rail from both sides.

A driving gear 33 is loosely mounted on the shaft 34. The gear 33 is in mesh with a gear 35 which is held by the shaft 35a. Another gear 36 is also held on the shaft 35a and is in mesh with the gear 37 which in turn is held on a shaft 37a. A gear 38 which meshes with the gear 39 is also held by the shaft 37a. The gear 39 is fastened to the driving shaft 31. A spiral winding spring 40 is held within the side frames 21 and 21x. One end of the spring 40 is held at 41 and the other end is fastened to the driving or winding shaft 34. The side frames 21 and 21x are held together by spacers 42 and 43. A brake finger 44 is hingeably mounted on a shaft 45. The brake finger 44 is manually operated by a brake arm 46. When arm 46 is raised the brake finger 44 will disengage the teeth of the gear 39 and allow the toy to be driven through the action of the spring 40. The depressing of the arm 46 will act to discontinue the operation of the toy. The monorail track 47 is supported in upright position by the cross ties 48.

A supporting leg 49 is fastened by screws or rivets 50 to the frame 21. The side frame 21x has bearings 52 which receive a hingeably mounted supporting leg 51. A coil spring 53 is wound around the leg 51 pressing same against the rail 47. The extension 54 of the supporting leg 51 serves in a manner to allow the operator to swing the leg 51 sideways when placing the toy over the monorail 47 as shown in dotted lines in Fig. 5.

As the monorail gage is constructed in sections which have to be fastened together there are provided on one end of the rail 47 a pair of prongs 48xx which are held by the cross ties 48. The other end of the rail has a cross tie 48 which carries a pair of holes 48x. When joining the rails together the prongs 48xx are inserted into the openings or holes 48x of the tie 48.

Referring to Fig. 7, this figure illustrates another modification of the hand car shown in Fig. 1. Instead of winding the spring 40 through a winding shaft 34 in this case the spring is wound through a hingeably mounted handle 30e. The handle 30e is hinging at the shaft 30 and operates a gear segment 30a which turns a gear 56 fastened to the spring winding shaft 55. A spring

30d serves to return the gear segment 30a. The other end of the spring 30d is placed in an opening 38c in the frame 21. The spring 40 operates a gear 59 through the ratchet wheel and arm 57 and 58. The gear 59 rotates a gear 60 which is fastened to the shaft 62. Another gear 61 is also fastened to the shaft 62 and is in mesh with the driving gear 63 which is fastened on to the driving shaft 31. To wind up the spring of the hand car shown in Fig. 7, the handle 30e is rocked up and down until the spring 40 is fully wound. Then the car is placed over the monorail and the bracket 46a is raised. The bracket 46a is hingeably held at 46b. A spring 46c is so arranged as to hold the bracket in both positions when it is necessary to run the toy or stop its operation.

In Fig. 8 is also shown a modified arrangement for joining the monorail links to each other. In this case a flat plate 69 is placed in between the links 47a and 47b of the monorail 47. This plate is spot welded to the rail 47 only at one of its ends. The other end of the rail is built into a packet or recess 69a to receive an extension of the plate 69 so that when the monorail links are placed end to end the plate 69 of one link is pushed into the recess of the other link. When such links are joined together the result will be a smooth and continuous rail.

In Figs. 10 and 11 is shown a monorail car train. Numeral 81 represents the body of the car. The train can be made to run through a spring wound motor or through an electric motor. In this case a spring wound motor similar to the one illustrated in Fig. 1 is used. To support the car on the monorail supporting legs 49 and 51 are shown which are similar to the legs used in Fig. 1. A different manner for supporting the monorail train on the rail gage is shown in Fig. 12. It consists of legs or arms 49 and 51. The lower part of these arms supports a pair of rollers 70. The rollers 70 contact the rail 47 from both sides. Rivets 71 are used in this case to secure the rollers to the arms 49 and 51.

In Fig. 6a, is shown a modified arrangement of a support for a monorail train. In this case instead of having a hingeable arm 51 and a stationary arm 49 a pair of springs 32b are used.

The train is placed upon the rail 47 by pressing the springs upon the rail until they clamp the rail 47.

The foregoing detailed description of the monorail hand car and monorail train has been given for clearness of understanding only and no unnecessary limitations should be understood therefrom, but it should be construed as broadly as permissible in view of the prior art.

While the monorail hand car and train herein illustrated and described is confined to certain structural details, I do not wish to limit myself to such details, but desire to cover all forms and arrangements, being only limited by the scope of the appended claims.

What I claim is:

1. A monorail toy hand car or the like vehicle including double flanged wheels adapted to run upon a single rail, and means for supporting said hand car in a straight and upright position upon said single rail, said supporting means including a stationary bracket secured to said car and contacting one vertical side of the frame of the rail, for a substantial distance and a manually operated bracket moveably secured to said car and contacting the other vertical side of the frame of said rail, said manually operated bracket hav-

ing a handle for operating said bracket and moving away from the frame of said rail when placing or removing said toy upon or from the single rail.

5 2. A monorail or the like vehicle including double flanged wheels adapted to run upon a monorail track, a stationary bracket secured to one side of the body of the monorail vehicle and contacting one vertical side of the frame of said track, for a substantial distance, and a manually hingeable bracket secured to the other side of the body of the vehicle and contacting the other vertical side of the frame of said track, said manually hingeable bracket having a handle, said handle being operated to hinge said bracket away from the frame of the track.

3. A monorail car having wheels adapted to run upon a single rail, means included for driving said wheels, and means for supporting said car in straight and upright position upon said single rail, said supporting means including a pair of brackets secured to said car and contacting either vertical side of the frame of said single rail, for a substantial distance one of said pair of brackets having a handle and being hingeably movable away from the frame of said rail for the purpose of facilitating the placing of said monorail car upon the single rail.

4. A monorail car including wheels adapted to run upon a single rail track, and means for preventing the tilting of said car, said tilting preventing means including a rigid member secured to said train and contacting one vertical side of the frame of said rail for a substantial distance and a manually operated member movably secured to said car and contacting the other vertical side of the frame of said car; said manually operated member moved outwardly and away from the frame of said rail, said outward movement of said movable member facilitating the placing of said car upon the single rail track.

5. A monorail car including wheels disposed in a single file thereon and being adapted to run upon a single rail track, propelling means for driving said wheels, and means for preventing the tilting of said train upon said track; said tilting preventive means including a stationary and a movable member attached to said train, the lower portion of said members comprising a shoe and contacting both vertical sides of said single rail, for a substantial distance said stationary member being rigidly mounted to said car, said movable member flexibly attached to said car, a handle attached to said movable member, the operation of said handle flexing said movable member outwardly in respect to the frame of said single rail when placing upon or removing said car from the single rail track.

6. A monorail car or the like vehicle including flanged wheels adapted to run upon a single rail track, means for balancing said car upon said track in a straight and upright position; said means including a bracket attached to said car and contacting one vertical side of the frame of said rail, for a substantial distance and a secondary bracket also attached to said car and contacting the other vertical side of the frame of said rail, the ends of the brackets contacting either vertical side of the frame of said rail having rollers thereon; said secondary bracket having an arm and being flexed away from the frame of said rail when placing upon or removing said car from the single rail track.
